HUMMINGBIRD FEEDER

Harry M. Brown, Jr., 3110 SE. Rex St.,
Portland, Oreg. 97202

Filed June 18, 1968, Ser. No. 12,405

Term of patent 14 years

Int. Cl. D30—02

U.S. Cl. D30—14

FIG. 2

FIG. 1

FIG. 3

FIG. 1 is a front view of a hummingbird feeder in accordance with my new design; and

FIG. 2 is a top view thereof; and

FIG. 3 is a bottom view thereof.

The broken line fragment of the hanging hook is shown for illustrative purposes only.

I claim:

The ornamental design for a hummingbird feeder, as shown and described.
